MOTOR FUEL DISPENSER

Guilbert M. Hunt, Willowick, Ohio

Application April 25, 1958, Serial No. 50,615

Term of patent 14 years

(Cl. D52—2)

FIG. 2

FIG. 1

Figure 1 is a perspective view of the motor fuel dispenser, illustrating one of the dial sides and the hose side; and

Figure 2 is an end elevation of the dispenser of Figure 1 showing my new design.

The opposite dial side of the dispenser, not shown, is substantially the same as the corresponding side which is shown.

I claim:

The ornamental design for a motor fuel dispenser, substantially as shown and described.
